UNITED STATES PATENT OFFICE

2,049,185

INDIRECT WATER HEATER

Allen B. Wilder, Chicago, Ill., assignor to
 Parkinson Heater Corporation, Chicago, Ill., a
 corporation of Illinois

Application January 18, 1935, Serial No. 2,416

1 Claim. (Cl. 257—236)

My present invention relates to improvements in conduction or indirect water heaters of the outside type. Conduction or indirect water heaters consist of loops or coils of tubing, through which the water to be heated is circulated, which tubing is disposed so that it is surrounded by the heating medium, usually the boiler water. Such heating coils are not infrequently inserted directly within the water compartment of the boiler. An outside type conduction heater is one in which a casing, other than the water compartment of the boiler, is provided within which the heat transfer tubing through which the water to be heated is circulated is disposed, the outside casing being connected with the boiler so as to secure a circulation, usually thermo-gravitational, of the boiler water through the casing and about the tubing.

In the designing of such apparatus no attention has formerly been paid to increasing the efficiency thereof by designing the structure so as to secure as efficient as possible a circulation of the boiler water through the outside casing. An increase in efficiency has heretofore been entirely sought and secured through an increase in the tube area through which the water to be heated is circulated and an increase in capacity of the casing in which the tubes are installed. Heretofore outside type conduction heaters have been excellent mud traps for sedimentation from the boiler water and also from the water to be heated.

I have had as my objects in the creation of the apparatus herein described and illustrated the increase of the efficiency of the apparatus by reason of securing a more efficient boiler water circulation therethrough, and the prevention of the sedimentation from the boiler water therein, and I have also had as an object the provision of a structure in which the heat transfer tubing may be cleaned more efficiently and with less trouble.

I have attained the foregoing objects by means of the structure illustrated in the accompanying drawing, in which—

Fig. 1 is a front elevation of an outside type conduction heater, partially in section, on line 1—1 of Fig. 2.

Fig. 2 is a top plan of the structure shown in Fig. 1.

Fig. 3 is a transverse section on line 3—3 of Fig. 1.

Fig. 4 is a fragmental elevation of a typical boiler with my structure in assembly therewith.

Similar reference characters refer to similar parts throughout the respective views.

The outside casing 5 is of a generally rectangular section, as best shown in Fig. 3, the center 6 of the top wall, however, being peaked, as shown in Fig. 1, so as to permit the entrance port 7 for the admission of the boiler water and opposite clean out opening 8, which is normally closed by a plug, being positioned at as elevated a point as possible with respect to the casing 5. The bottom of the casing has the walls 9 from the ends of the casing and the walls 10 from the sides of the casing slope downwardly to converge upon a hub 11 which is interiorly threaded for connection with the return 12 to the boiler 13, the entrance port 7 of the casing being connected by a nipple 14 with the boiler 13 just below the water line thereof. The rectangular ends of the casing are closed by webs 15 and 16, which webs are perforated for receiving the ends of the heat transfer tubes 17. Beyond the web 15 the casing is continued and provided with a transverse partition 17a to provide an entrance chamber 18 communicating with the lower rank of heat transfer tubes and a discharge chamber 19 communicating with the upper rank of heat transfer tubes. Beyond the web 16 the casing is continued to provide a single chamber 20 into which flows the water through the entrance chamber 18 through the lower rank of heat transfer tubes and from which flows the water from the upper rank of heat transfer tubes to the discharge chamber 19.

An entry port 21 is provided upon the bottom of the extended end of the casing communicating with the entrance chamber 18 and a discharge port 22 is provided upon the top of the casing communicating with the discharge chamber 19. The ends of the chambers 18 and 19 are closed by a single plate 23 secured in position by suitable machine screws 24, or in any other suitable way, and the chamber 20 is closed by a plate 25 secured in position in the same manner. The service water supply pipe 26 is attached to the inlet port 21 and the pipe 27 leading to the fixtures is secured to the discharge port 22.

When this device is functioning the boiler water is heated and service water is passing through the tubing 17 from the port 21 and out through the port 22 to the fixture or to the hot water storage tank. Such a condition results in the cooling of the boiler water in the vicinity of the tubes 17. The cooling of this water causes its contraction and increase of weight and it sinks down through the inclined bottom of the casing through the return pipe 12 to the bottom of the boiler and as the cold water sinks by its increased weight the lighter, hotter boiler water

flows in from the top of the boiler through the pipe 14 and the port 7. The length of the leg or column of falling cooled water in the casing 5 and pipe 12 materially affects the rapidity of the circulation. If the nipple 14 were connected with the top of the casing, instead of the side of the casing at the top, it would be necessary to subtract the height of the connection from the length of the return as the weight of the length 10 of the return would actually have to pull the lighter water down in a direction in which it naturally would not flow until it came in contact with the heat transfer tubes 17.

In the construction hereinbefore described and illustrated none of the weight of the descending cooled leg of water is sacrificed in pulling hot water down into contact with the heat transfer tubes. The inclined or oblique walls of the bottom of the casing, together with the increased circulation of the boiler water therein, prevents the precipitation of sedimentation in the casing and all sedimentation is returned to the boiler where its removal is ordinarily provided for.

It is obvious by a glance at Figs. 1 and 3 of the

drawing that when the end plates 23 and 25 are removed from the casing the entire length of the heat transfer tubes 17 are opened for cleaning out in a most thorough and satisfactory manner.

The additional circulation of boiler water I 5 secure through the heater casing secures a surprising increase in efficiency in the heating of the service water supply.

Having described my invention what I claim is new and desire to secure by Letters Patent is: 10

A conduction water heater of an outside type comprising a casing having a hopper bottom and having opposed parallel tube webs or headers with tubes extending therebetween, an inlet and a discharge chamber communicating with groups 15 of said tubes at one end of said casing and a compartment at the other end of said casing with which all of said tubes communicate, removable closures for the compartments at the ends of said casing, an inlet port to said casing on a level with 20 the top row of said tubes, and a hub at the lower end of said hopper for connection with the return to the boiler.

ALLEN B. WILDER.
